UNITED STATES PATENT OFFICE.

HARRY ROSS, OF LONDON, ENGLAND.

FOUNTAIN PEN.

Application filed October 13, 1922. Serial No. 594,306.

To all whom it may concern:

Be it known that I, HARRY Ross, a subject of the King of England, residing at 50-51, Pall Mall, London, Kingdom of England, have invented certain new and useful Improvements in or Relating to Fountain Pens, of which the following is a specification.

This invention relates to improvements 10 in self filling fountain pens of the kind having a collapsible resilient ink reservoir arranged within the barrel of the pen and adapted to be compressed by a bar actuated by a pivoted lever in order that ink may 15 be drawn into the reservoir when the pressure thereon is released.

In the present-day self-filling fountain pens it has been found that the reservoir can only be partially filled with ink; therefore, the pen has to be replenished with ink 20 at frequent intervals. It is the object of this invention to provide improved means for actuating the reservoir collapsing bar in such a manner that the reservoir can be 25 substantially or completely filled with ink when the refilling operation is performed.

A further object is to provide means which so actuate the reservoir collapsing bar that the air is expelled from the rear 30 portion of the reservoir before the front portion thereof.

With these and other objects in view the invention is characterized in that the rear portion of the collapsible ink reservoir is 35 collapsed before the front portion thereof.

The invention further consists in actuating the reservoir collapsing bar through the medium of a plurality of connected levers or links which are adapted to be operated 40 by a lever or other suitable means arranged exteriorly of the pen reservoir.

The invention will now be described with reference to the accompanying drawings, in which:—

45 Figure 1 is a longitudinal sectional elevation of one form of pen constructed in accordance with this invention showing the collapsing bar when in its depressed position in full lines and when in its normal position by dotted lines;

Figure 2 is a cross section taken on the line 2—2 of Figure 1;

Figure 3 is a similar view to Figure 1 showing the collapsing bar partly depressed;

50 Figure 4 is a longitudinal sectional elevation of a part of a self filling fountain

pen showing a modification of the invention, and

Figure 5 is an inverted plan of the operating lever shown in Figure 4 and the casing for the levers and links.

As shown more particularly in Figures 1 to 3, the body *a* of the pen which is adapted to contain a flexible bag reservoir *b* in the usual manner is longitudinally slotted at *c* 65 for the reception of a plurality of transversely arranged pivot pins *d*. On each of these pivot pins *d* is pivotally mounted a lever, link or the like *e*, *f*, *g*. The lever *e* is formed with an outward extension or 70 handle *h* whereby it may be actuated from the exterior of the pen. This actuating lever *h* is adapted to lie substantially flush with the body *a* of the pen when in its inoperative position. This operating lever *h* 75 is preferably shaped at its outer end to provide a handle or grip *i* whereby it may be conveniently moved to its operative position. This handle or grip portion *i* of the lever *h* is adapted to lie in a recess or the like *j* formed in the barrel *a* of the pen. To the inner end of the operating lever *e* and the lever, or links *f*, *g* is pivoted in any suitable manner a connecting bar or the like *k*. The arrangement is such that the parts are adapted to act substantially as a parallel rule movement. The ends of the levers or the like *e*, *f* and *g* are, upon the 80 operation of the operating lever *h*, adapted to act upon a reservoir collapsing bar *l* 90 which latter extends preferably the full length of the bag reservoir *a* and is of curved shape in cross section. The rear lever or link *g* is enlarged or formed with an extension *m* which is adapted when the 95 device is operated to engage with the reservoir collapsing bar *l* before the other levers or links. When the operating lever *h* is moved to a substantially vertical position, the reservoir collapsing bar *l* presses on the 100 bag *b* to collapse it for the refilling operation in the usual manner, but during the collapsing of the bag *b*, the collapsing bar *l* is tilted so that the rear end of the bag will be collapsed before the front end of the bag *b* which is connected in the usual manner to the nib carrier *n* in which is mounted the feed bar *o* adapted to feed the nib *p*. Thus 105 the air in the bag *b* will be expelled in the direction from the rear end of the bag and the bag will collapse in such a manner that no air locks will occur. When the operat-

ing lever *h* is moved back to its initial position during the refilling of the pen, the ink will be drawn into the reservoir *b* and will completely fill the same.

5 In a slightly modified construction, as shown more particularly in Figures 4 and 5, the pivot pins *d* of the levers or links *e*, *f* and *g* which may be constructed of U-shaped material are mounted in a box like device *q*, 10 preferably constructed of metal. This box like device *q* is of substantially U-shape in cross section to provide a pair of longitudinal flanges *r* and an intermediate portion *s* which is adapted to conform to the body *a*, 15 of the pen. This intermediate portion *s* is extended at each end to provide ears *t* which are adapted to be connected to the body of the pen in any convenient manner, preferably by screws *u* passing through holes in 20 the said ears *t* and screwing into the body *a* of the pen which latter is constructed of vulcanite or other suitable material. In this case the intermediate lever *h* is adapted to extend through the slot in the intermediate 25 portion *s* of the box member *q* and this lever *h* is shaped to provide a handle or operating lever. The operation is similar to that previously described in connection with the other construction. It will be understood 30 that other means may be provided to incline the reservoir collapsing bar during its movement on the bag, such as an extension or hump *v* formed or provided on the connecting bar or the like. Further, any number of 35 levers or links may be employed to operate

the collapsing bar or only two levers may be employed.

Thus it will be seen that I have provided operating means for an ink reservoir which are extremely neat and simple in construction and which will enable the reservoir to be more completely filled with ink. 40

What I claim is: —

1. A self-filling fountain pen, having a collapsible ink reservoir, a bar for compressing the same, and a plurality of connected levers for operating on the bar, one of said levers having an extended free end to cause said lever to engage and operate the bar in advance of the bar engagement of the remaining levers. 45

2. A self-filling fountain pen, having a collapsible ink reservoir, a bar for operating said reservoir, a support secured in a slot formed in the pen barrel overlying said bar, said support having depending spaced side walls, and an outer wall to complete the barrel formation when the support is in position in the slot, a series of levers pivotally connected between said side walls, a strip 55 connecting the levers adjacent their free ends to insure simultaneous movement of such levers, one of the levers having its free end extended to engage and operate said bar in advance of the bar engagement of the remaining levers, and means for simultaneously operating said levers. 60

In testimony whereof I have hereunto signed my name.

HARRY ROSS.
